CLAIM

The ornamental design for a fishing rod rack, as shown and described.

DESCRIPTION

FIG. 1 is a top front perspective view of a fishing rod rack, showing my new design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 2;

FIG. 11 is an enlarged detail view of area 11 in FIG. 3;

FIG. 12 is an enlarged detail view of area 12 in FIG. 7; and,

FIG. 13 is an enlarged detail view of area 13 in FIG. 8.

The broken lines in the drawings illustrate the portions of the fishing rod rack, which form no part of the claimed design. The dash-dot-dash broken lines encircling the enlarged views are for annotative purposes only and form no part of the claim thereof.
